UNITED STATES PATENT OFFICE.

GLENN W. CARPENTER, OF SCHENECTADY, NEW YORK, ASSIGNOR TO GENERAL ELECTRIC COMPANY, A CORPORATION OF NEW YORK.

VACUUM-TUBE CIRCUIT.

Application filed October 27, 1923. Serial No. 671,254.

My invention relates in particular to the use of vacuum tubes in receiver and transmitter circuits, and the object of the invention is to simplify the apparatus used in such circuits, for the detection and amplification of received signals, for the amplification of transmitted signals, and for the modulation of currents in signal transmission.

The principle involved in this invention 10 may be used in circuits for radio telegraphy, radio telephony, or wire telegraphy and telephony.

A fundamental feature of the invention is the enclosure within a single vacuum chamber of the elements of a plurality of vacuum tube devices such as are familiar in the art of radio communication, the several sets of elements being capable of functioning normally and independently of each other. An 15 other fundamental feature of the invention is the use of but a single filament with a plurality of such sets of elements.

Other advantages and uses of the invention 20 will appear in the description and drawings, which follow.

In the accompanying drawings:

Fig. 1 is a circuit diagram showing the use 25 of the improved tube as a radio frequency detector and a one-step amplifier;

Figure 2 is a circuit diagram showing the use 30 of the improved tube as a two-step amplifier;

Figure 3 is a circuit diagram showing the use 35 of the improved tube as a detector and multistage amplifier;

Figure 4 is a circuit diagram showing the use 40 of the improved tube as a transmitter in radio telephony or telegraphy; and

Figure 5 is a circuit diagram showing the use 45 of the improved tube as a multistage amplifier, using a combination of resistance and capacity coupling between successive stages.

Referring to Figure 1, one plate P_1 , one grid G_1 , and the filament F are used as a 50 detector in the usual way, with the blocking condenser C_1 , or, as indicated in dotted lines, without it. The other half of the tube, comprising plate P_2 , grid G_2 and filament F , is used as an amplifier. The leads marked 1 and 2 are the input terminals and are connected to the voltage supply to be detected 55 and amplified in the usual manner familiar in the art.

The first plate P_1 is connected through the primary p of a transformer T to the so-called "B" battery or plate battery B . A large capacity C_3 is connected in shunt to the B battery to form a low impedance path for the alternating current. A capacity C_2 may be connected in shunt to the primary p for 60 tuning to any desired frequency.

The secondary s of transformer T is connected to the second grid G_2 and to the negative side of the filament F which is supplied with current from the "A" battery or filament 65 heating battery A . Proper polarity of the transformer connections must be carefully observed or else troublesome "howling" is likely to occur. The plus and minus signs on the drawings refer only to the alternating 70 components of the currents at a particular instant.

The operation of this arrangement is as follows: A varying potential is impressed on the terminals 1 and 2. If this varying potential is in the form of a damped high frequency oscillation, the elements P_1 , G_1 , and F function as a detector in the usual way known in the art. The audio frequency current existing in the plate circuit P_1 due to this detector 80 action may then be transferred to the input circuit of the other half of the tube by any unstable coupling means known in this art, shown in Figure 1. Two transformers T_1 , The second grid-and-plate set amplifies the 85 audio frequency signal as though it were in an entirely separate tube. The translating devices, such as telephones or a recorder, are connected in the plate circuit P_2 .

The circuit for a two-stage amplifier, shown 90 in Figure 2, is almost identical with that shown in Fig. 1. Two transformers T_1 and T_2 are used, and both sides of the tube are used as amplifiers. Capacities C_5 and C_6 , like capacity C_2 in Fig. 1, are used for tuning 95 the circuit to take the desired frequency. Terminals 3 and 4 are the input terminals and may be connected in circuit with the detector (not shown) whose output is to be amplified. Here again the polarities marked 100 on the transformers in Figure 2 are correct only when speaking of the alternating components of the currents at a particular instant.

The same principle as illustrated in Figure 105 1 may be applied to a tube containing several

grid-and-plate sets with a common filament arranged to form a detector and a multistage amplifier as shown in Figure 3. Each of the above grid-and-plate sets may consist of a plurality of grids and a plurality of plates, all associated with a common filament, and each group of grid-and-plate sets acting as a separate vacuum tube. The action is the same as in Figure 1. The output circuit of the second grid-and-plate set is coupled to the input circuit of a third grid-and-plate set through one of the coupling devices mentioned above. The translating device is connected in the output circuit of the third grid-and-plate set as shown in Figure 3. This cascade arrangement may be used for any number of steps of amplification.

Figure 4 illustrates a method of using the principle involved in my invention, in the amplification of modulations in undamped signal transmission as in radio telephony, or in the amplification of radio frequency currents in undamped radio telegraph transmission. The elements P_1 , G_1 and F are connected to form an oscillating circuit in the usual way. This may be accomplished by connecting the primary p and the secondary s of a transformer T_1 in the plate and grid circuits respectively of the first grid-and-plate set. The oscillating energy in the plate circuit is then repeated to the grid G_2 of the second grid-and-plate set by means of a second transformer T_2 . The elements P_2 , G_2 and F serve as an amplifier of the energy supplied by the first grid-and-plate set. The antenna and ground may be connected to the coil Q in circuit with the plate P_2 . The key K may be used to operate the device as an undamped wave transmitter. To use the device as a transmitter of the human voice, the operator speaks into the microphone M . The undamped oscillations produced by the first grid-and-plate set are modulated by the voice currents in the secondary of the transformer T_3 . The modulated energy is then amplified by the second grid-and-plate set and communicated to the antenna by the coil Q .

Figure 5 illustrates a method of using the improved tube as a cascade amplifier, the successive steps being coupled by a combination of resistance and capacity. This arrangement is very desirable for radio frequency amplification. The last grid-and-plate set acts as a detector in the usual way, while the preceding ones act as radio frequency amplifiers.

What I claim as new and desire to secure by Letters Patent of the United States, is:

1. The combination in a system for the reception of electric impulses, of a vacuum tube enclosing a single filament and a plurality of grid-and-plate sets each of which comprises an individual grid and plate associated therewith all of which are so located with respect

to the filament that electrons may be received from the entire length thereof, circuits connecting said filament and grid-and-plate sets in cascade and a common source of energy for supplying all of the current to all of the plates.

2. The combination in a system for the communication of electric impulses, of a vacuum tube enclosing a filament and a plurality of grid-and-plate sets associated therewith all of which are so located with respect to the filament that electrons may be received from the entire length thereof, an input circuit connected to a detector group of said grid-and-plate sets, cascade amplifier circuits connected between said detector group and the remaining grid-and-plate sets and a common source of energy for supplying all of the current to all of the plates.

3. The combination in a system for the communication of electric impulses, of a vacuum tube enclosing a filament and a plurality of grid-and-plate sets each of which comprises an individual grid and plate associated therewith all of which are so located with respect to the filament that electrons may be received from the entire length thereof, coupling means, and circuits connecting said filament and grid-and-plate sets in cascade by said coupling means and a common source of energy for supplying all of the current to all of the plates.

4. The combination in a system for the communication of electric impulses, of a vacuum tube enclosing a filament and a plurality of grid-and-plate sets each of which comprises an individual grid and plate associated therewith all of which are so located with respect to the filament that electrons may be received from the entire length thereof, induction coupling means and circuits connecting said filament and grid-and-plate sets in cascade by said coupling means.

5. The combination in a system for the communication of electric impulses, of a vacuum tube enclosing a filament and a plurality of grid-and-plate sets associated therewith, circuits connecting said filament and one group of grid-and-plate sets arranged to generate and modulate an alternating current, and cascade amplifier circuits connected between said first group and the remaining grid-and-plate sets.

6. An amplifying valve having a filament and two grid-and-plate pairs symmetrically grouped respectively on each side of the filament to form a six terminal valve, the two grid-and-plate pairs being arranged in cascade connection by inductive coupling means.

7. In a telephone receiving circuit, an amplifying valve having a filament and two grid-and-plate pairs symmetrically grouped respectively on each side of the filament to form a six terminal valve, the grid of one pair and a filament terminal being connected

to the circuit from which the signals are received, the plate of the same pair being connected to a filament terminal, a direct current source in circuit therewith, a transformer having its primary coil in said plate-filament connection, a third circuit, including the grid of the other pair, the secondary

5 of said transformer and a filament terminal, and a fourth circuit, including the plate of the second pair, said direct current source, a 10 telephone and a terminal of the filament.

In witness whereof I have hereunto set my hand this 26th day of October, 1923.

GLENN W. CARPENTER.

CERTIFICATE OF CORRECTION.

Patent No. 1,723,013.

Granted August 6, 1929, to

GLENN W. CARPENTER.

It is hereby certified that error appears in the printed specification of the above numbered patent requiring correction as follows: Page 1, line 84, strike out the words "shown in Figure 1. Two transformers $T_{sub 1}$ " and insert instead "for instance, an inductive transformer T ."; and that the said Letters Patent should be read with this correction therein that the same may conform to the record of the case in the Patent Office.

Signed and sealed this 10th day of September, A. D. 1929.

(Seal)

M. J. Moore,
Acting Commissioner of Patents.

to the circuit from which the signals are received, the plate of the same pair being connected to a filament terminal, a direct current source in circuit therewith, a transformer having its primary coil in said plate-filament connection, a third circuit, including the grid of the other pair, the secondary

of said transformer and a filament terminal, and a fourth circuit, including the plate of the second pair, said direct current source, a telephone and a terminal of the filament.

In witness whereof I have hereunto set my hand this 26th day of October, 1923.
